UNITED STATES PATENT OFFICE.

WILLIAM FRANK ZIMMERMANN, OF WAVERLY, NEW YORK, ASSIGNOR TO INGERSOLL-RAND COMPANY, OF JERSEY CITY, NEW JERSEY, A CORPORATION OF NEW JERSEY.

FLUID-ACTUATED PERCUSSIVE MACHINE.

Application filed June 4, 1925. Serial No. 34,775.

This invention relates to fluid actuated percussive tools or machines, but more particularly to a hand held machine in which the piston reciprocates in the cylinder and is controlled by a fluid actuated distributing valve. In the present embodiment of the invention the piston is provided with a shank or piston rod so that the machine is of the piston drill type and is particularly useful as a sand rammer.

The objects of the invention are to improve the construction and operation of the automatic distributing valve which in this instance controls only the inlet of live pressure fluid to the cylinder. A free exhaust in the side of the cylinder is controlled only by the piston and the valve itself is an improvement on the so called type of current valve in which the flow or current of pressure fluid in conjunction with the drop of pressure beneath one end of the valve and compression of fluid by the piston exerted against the other end of the valve causes the valve to operate.

In accordance with this improved construction, the valve is light, consumes a small amount of space, and may be conveniently located rearwardly of the cylinder in a valve box in line with the cylinder.

The invention is illustrated in one of its preferred forms in the accompanying drawings, in which:

Figure 1 is a longitudinal sectional elevation of so much of a sand rammer as will serve to make the invention clear,

Figure 2 is a similar view with the piston in a different position,

Figure 3 is a detail transverse sectional view taken on the line 3-3 of Figure 1 looking in the direction of the arrows, and

Figure 4 is a detail side elevation of the valve.

Referring to the drawings, the cylinder A is provided with the reciprocating piston B having the forward extension or piston rod C extending through the gland D preferably having packing material E. The forward end of the piston extension C is shown broken away, but it is to be understood that this forward extension or piston rod may be provided with any suitable tool or implement for the purposes desired, as for instance, the piston rod may be equipped with a sand ramming head.

The back head F having the inlet G for

live pressure fluid may be secured to the cylinder A in any suitable manner, and within the back head rearwardly of the cylinder and in line therewith is located a valve box containing the valve H.

As shown the valve box comprising the front section or block J and the body K, between which the valve H is located in a shallow circular recess L in the body K, is a convenient construction.

The valve H is a comparatively thin plate valve in the form of an oscillating circular disk uniformly tapered from its median diameter O towards the periphery at each side so that the valve oscillates about its center axis. The valve disk is preferably cut on the cords of the circle at opposite sides to form the straight edges P and Q and thus permit the live pressure fluid to pass over the said straight edges of the valve and through the clearance space thus provided to the cylinder. The valve is preferably guided in a suitable manner as by means of the pins R extending through the valve with slight but sufficient clearance in 80 the valve to permit the valve to rock freely. Sufficient clearance is also provided between the periphery of the valve and the valve box to prevent binding and permit free oscillation.

The body K of the valve box is provided with the inlet passages S and the block or valve box section J is provided with the inlet ports T and U controlled only by the valve. The inlet port T leads to the rear end of the cylinder while the inlet port U communicates with the inlet passage V leading to the inlet port W at the forward end of the cylinder. An exhaust passage X in the cylinder communicates with the atmospheric exhaust port Y at one end and with the exhaust port Z located centrally of the cylinder. As shown there may be two exhaust ports Z communicating with the exhaust passage X.

In the operation of the device, let it be assumed that the piston is at the rear end of the cylinder as indicated in Figure 1 with the valve H also in the position indicated, so that the live pressure fluid entering at 105 the inlet G holds the end Q of the valve down over the inlet port U, the under side of the valve at this end being at atmospheric pressure through the cylinder and exhaust port Y. Live pressure fluid passes over the 110

end P of the valve and through the inlet port T to the rear end of the cylinder to drive the piston B forwardly.

- In Figure 2 the piston B is shown substantially at the end of its forward stroke and is returning on its rearward stroke since the valve H is rocked to its opposite position closing the inlet port T and opening the inlet port U to the forward end of the cylinder. As the piston B uncovers the rearward exhaust port Z in its forward stroke, the pressure beneath the end P of the valve is dropped underneath the entire surface of one half of the valve so that the live pressure fluid on top of the valve tending to flow over the valve and the compression pressure beneath the opposite end of the valve actuates the valve and closes the inlet port T causing the valve to open the inlet port U. From this point the cycle is repeated as the piston reciprocates.

I claim:—

1. A fluid actuated percussive machine, comprising a cylinder and reciprocating piston, a free exhaust port located centrally of the cylinder and controlled only by the piston, a valve box having a seat portion and a shallow circular recess located at the rear end of the cylinder and in line therewith, a plate valve in the form of a thin

flat, oscillating circular disk in said shallow valve box recess, said valve disk being uniformly tapered from its median diameter towards the periphery at each side, and bearing on the seat portion of the valve box along said median diameter, and inlet ports in the seat portion of the valve box for the ends of the cylinder controlled only by the valve.

2. A fluid actuated percussive machine, comprising a cylinder and reciprocating piston, a free exhaust port located centrally of the cylinder and controlled only by the piston, a valve box having a seat portion and a shallow circular recess located at the rear end of the cylinder and in line therewith, a plate valve in the form of a thin, flat oscillating circular disk seated in said shallow valve box recess, said valve disk having clearance at opposite edge portions and being uniformly tapered from its median diameter towards said opposite edge portions, and inlet ports in the seat portion of said valve box for the ends of the cylinder controlled only by said opposite edge portions of the valve.

In testimony whereof I have signed this specification.

WILLIAM FRANK ZIMMERMANN.
